UNITED STATES PATENT OFFICE.

REX PACKWOOD, ERWIN J. RUST, AND EUGENE HAZELETTE, OF CLEVELAND, OHIO.

MOTOR-DRIVEN CLIPPER.

1,281,214.

Specification of Letters Patent.

Patented Oct. 8, 1918.

Application filed August 1, 1917. Serial No. 183,917.

To all whom it may concern:

Be it known that we, REX PACKWOOD, ERWIN J. RUST, and EUGENE HAZELETTE, citizens of the United States, residing at Cleveland, in the county of Cuyahoga and State of Ohio, have invented new and useful Improvements in Motor-Driven Clippers, of which the following is a specification.

This invention is a motor driven clipper 10 that may be used upon human beings as well as animals with equally good results in the trimming of hair or fur.

One object of this invention is to provide a clipper with an electric motor where- 15 in the construction is simple, strong, and durable.

Broadly stated, the invention comprises an electric motor having a suitable control therefor, the shaft of the motor being pro- 20 vided at one end with a worm, a frame adapted to be secured to one of the end frames of the motor so that the shaft and worm project therethrough, a housing for said frame, a shaft upon which is mounted 25 a gear to mesh with the worm, a cam on said gear, a pivotally mounted lever, one end of which is provided with a yoke to coöperate with the cam, the other end being provided with a connecting end so that it may be op- 30 eratively connected with the cutting blades or cutting comb, comb teeth positioned adjacent the cutter blades and secured to the frame, the work meshing with the gear and imparting a rotary motion to the eccentric so 35 that the lever and its yoke may produce a reciprocating and rectilinear motion of the cutting blades relative to the comb blades which are stationary.

One practical form will be described and 40 illustrated in the accompanying drawing, in which:—

Figure 1 is in part a vertical sectional view.

Fig. 2 is a plan view of the cam, lever, and 45 gear showing the connection.

In the preferred embodiment shown, an electric motor 6 is provided that is suitably inclosed by the end frames 7 and 8.

Suitable controlling means may be po- 50 sitioned in the end frame 8, as indicated by the button 9. The end frame 8 may be pro- vided with a flange 10 and through this flange 10 and end frame 8 projects the ar- mature shaft 11, which carries at its outer 55 end the worm 12. To coöperate with the flange 10 is a frame 13 which is provided

with a suitable groove 14. This groove 14 may be of such width and depth as to adapt it to coöperate with the flange 10 so that when the frame 13 is connected to the flange 60 10 it may be securely held as by the set screw 15.

Preferably positioned upon the frame is another flange indicated at 16, that is adapt- 65 ed to coöperate with the housing or cap 17. As shown, the housing 17 is provided with an inturned flange 18 at one end. A groove is formed between the flange 16, and the frame 13 which forms a seat for the flange 18 of the housing 17.

The other end of the housing 17 coöper- 70 ates with the cutting comb 19 and is adapted to be placed in close proximity thereto to limit the vertical movement of the cutting comb. The housing 17 may be secured to 75 the frame 13 in any usual manner, and they are shown as being connected together by means of a bolt having a head 20, a threaded stem 21, and a sleeve or bearing portion 22.

The threaded stem 21 projects upwardly 80 through a suitable aperture formed in the housing 17, and to hold the screw in position a nut 23 is employed. When the nut 23 is in operative position, the head 20 bears against and is seated within a suitable re- 85 cess 24 formed in the bottom or lower side of the frame 13, and the pressure exerted by this nut 23 holds the housing 17 and the frame 13 in a predetermined position. It may also serve to produce tension by a fric- 90 tional engagement of the outer end of the housing where it contacts with the cutting comb 19.

The frame 13 may be provided interiorly 95 with suitable bearings one of which is shown in Fig. 1. As illustrated, it comprises a base 25 and an upstanding portion 26 which has an aperture forming the bearing for the shaft 27. The base 25 is secured to the frame 13 in a suitable manner as shown by 100 the screw 28.

The shaft 27 has mounted thereon a gear 29 that is adapted to mesh with the worm 12. If desired, the gear may revolve on the shaft, and further, the gear may be pro- 105 vided with an anti-friction bearing.

The gear 29 is provided on each side with hubs 30 and 31 whose lateral faces form cams. To coöperate with the lateral faces a lever 32 is provided which has one end 110 formed with engaging portions shown by the fingers 33 and 34. This lever is pivot-

ally mounted upon the bearing portion 22 of the bolt, and has extending from the body 34^a of the lever, an arm 35 which terminates in a sector end 36. The cutting comb is 6 provided with a solid or body portion 37 that is connected to the lever through the sector 36 which operates in a suitable recess 38 formed in said body portion.

As shown, the lever 34 has its projecting arms extending in different horizontal 10 planes to coöperate with the cams and with the body 37 of the cutting comb 19.

To coöperate with the cutting comb 19, the comb teeth 39 are provided. The comb 15 teeth are carried upon a frame indicated at 40, which is provided with a suitable hole through which passes certain holding means, one of which is indicated by the screw 41, that holds it in engagement with the 20 frame 13.

As shown the frame 41 is stationary and also forms an additional seat which tends to hold the head 20 of the bolt holding the frame 13 and the housing together into firm 25 engagement with the seat of the flange in the underside of the frame 13. The frame 40 is provided with a shallow groove 40^a which lies back of the teeth 39 of the comb portion. This groove serves to permit the 30 cutting comb 19 to have two supports, one upon the frame 40, and the other in contact with the comb teeth 39.

As shown, the cutting comb 19 in its reciprocation has one edge and side abutting 35 against the frames 13 and 40. As shown more particularly in Fig. 1, the frames 13 and 40 provide a shouldered portion to form this bearing at their juncture.

Minor changes in the form, proportions, and details of construction may be resorted 40 to without departing from the spirit of the invention or the scope of the appended claim.

What is claimed as new is:—

A device of the class described comprising a hollow handle having a flange at one end, a motor in said handle having a shaft extending beyond the same, a frame having a recess for receiving the flange, means for removably securing the flange in said recess, 45 a screw threaded bolt having its lower end carried by the bottom of the frame and extending upwardly, a housing engaging with the upper end of said bolt and provided with a flange, said frame having a recess 50 to receive said flange, a nut adjustably securing the housing in place on the bolt, a plate removably secured to the bottom of the frame and covering the bottom of the bolt, comb teeth formed on the outer end of 55 said plate, said plate having a recess therein adjacent the base of the teeth, a movable cutting comb coöperating with the cutting teeth and provided with a projecting portion engaging said recess, a lever connected 60 with said cutting comb and having a part engaging with said bolt, and cam means operated by the shaft of the motor and engaging with a part of the lever for operating the same.

In testimony whereof we affix our signatures.

REX PACKWOOD.
ERWIN J. RUST.
EUGENE HAZELETTE.
